UNITED STATES PATENT OFFICE
Tomlinson, Fort Johnson, Atlanta, Ga.
Application May 16, 1941, Serial No. 393,823
1 Claim. (Cl. 200—48)

This invention relates to high tension electric switches and, among other objects, aims to provide a greatly improved switch of the rocking insulator type so constructed as to permit the blade tip to have compound longitudinal and swinging movement and coacting with a high pressure contact provided with a sleet hood.

Other aims and advantages of the invention will appear in the specification, when considered in connection with the accompanying drawings, wherein:

Fig. 1 is a side elevation of a switch unit of the rocking insulator type embodying the invention;

Fig. 2 is a fragmentary top plan view of Fig. 1 showing the switch blade and associated parts;

Fig. 3 is a fragmentary side elevation similar to Fig. 1 but showing the switch blade in a different position;

Fig. 4 is a fragmentary, enlarged horizontal sectional view taken on the line 4—4 of Fig. 3; and

Fig. 5 is a fragmentary, enlarged vertical sectional view taken on the line 5—5 of Fig. 3.

Heretofore, air-break switches of the rocking type usually have had their switch blades rigidly mounted on a rocking insulator with the result that, when the insulator is rocked, the tip of the switch blade swings in a true arc. The tip, being the point farthest from the pivot point of the insulator requires the maximum power to release it from the switch jaws. Also, the jaws must be open at the top to permit the tip to swing to open and closed positions. The present invention provides a novel arrangement in which a rigid switch blade is pivotally mounted at its rear end on the rocking insulator so that the tip of the blade moves longitudinally out of the jaws and swings upwardly in an arc and vice versa. This construction requires less power to operate the switch and permits greater spring pressure to be used on the jaws.

Referring particularly to the drawings, the switch structure is shown as being mounted on an ordinary structural channel 10 carrying a stationary insulator 11 at one end on which ordinary floating spring contacts or jaws 12 having a terminal 13, are mounted. A rocking insulator 14 having a conventional operating arm 15 is mounted on the channel intermediate its ends and carries a switch blade assembly 16 cooperating with the contacts 12. A third insulator 17 is mounted on the other end of the channel and carries a conventional terminal 18, as well as the rear end of the usual articulated conductor 19.

The blade assembly 16 is here shown as comprising a blade carrier 20 having upwardly bent

spaced ears 21 at its rear end mounted on a pivot pin 22 carried by an upstanding web 23 on a plate 24 secured to the cap of the rocking insulator 14. A blade 25 is secured to the forward end of the blade carrier and is shown as being composed of a pair of strap metal members 26 preferably made of copper. Their forward ends are secured together forming the blade tip 27 and their rear ends are spaced apart to straddle the forward end portion or tongue of the blade carrier 20 to which they are shown as being secured by bolts 28.

When the switch is in closed position, the blade is supported substantially horizontally on a ledge 29 forming part of the sleet housing and support 30 for the jaws. The ledge 29 also serves to guide the blade tip 27 longitudinally into and out of the jaws 12. The rocking insulator 14 is limited in its swinging movement to stop the blade in that position by an adjustable stop member 31 carried by the insulator and arranged to strike a buffer or spring plate 32 on the channel support (Fig. 1). The blade is biased against the ledge 29 by coiled springs 33 connected to a cross rod 34 extending between the ears 21 and to the opposite sides of the web 23.

As the insulator 14 is rocked initially rearwardly, the rear end of the blade carrier swings counterclockwise; while the tip of the blade moves substantially longitudinally to the left, being prevented from moving upwardly due to the frictional engagement of the spring jaws 12 and the tension of the springs 33. As the rearward movement of the insulator continues, a lug 35 on the bottom of the blade carrier strikes an adjustable stop 36 carried by a forward extension on the plate 24. At this point, as best shown in Fig. 3, the extreme forward end of the tip 27 has moved rearwardly sufficiently to clear the rear end of the top wall of the sleet hood or housing 30. The blade assembly 16 and insulator 14 will then swing as a unit to its fully open position, as indicated by dotted lines in Fig. 1.

In order that arcing horns may be employed to cooperate with the usual arcing rod 37, the plate 24 is shown as having a horn-shaped bracket 38 extending upwardly and forwardly around the upper rear end of the blade carrier to which the horns 39 are secured. Incidentally, the bracket has lateral reinforcing flanges 40 above the pivoted end of the blade carrier which also serve as a sleet hood. The forward end of the articulated conductor 19 is also shown as being pivotally connected to the bracket 38 and flexible

cables 41 are shown as being connected to the blade members 26 and to the conductor 19.

When the insulator 14 is rocked clockwise, to close the switch, the blade 25 moves with it as a unit until the bottom front edge of the blade tip 27 strikes the top surface of the ledge 29 (Fig. 3). Continued clockwise movement causes the insulator 14 and the rear pivoted end of the blade carrier 20 to swing in an arch, while the tip 27 of the blade, supported on the ledge 29, is forced substantially longitudinally into the spring jaws 12.

The blade carrier 20 is shown as having an upstanding stop lug 42 spaced slightly beneath the overhanging portion of the bracket 38 when the switch is in closed position (Fig. 1). This lug is adapted to strike the bracket 38 and limit the upward movement of the blade carrier 20 relative to the bracket when the switch is in open position to prevent the springs 33 from being overstretched and also to prevent the blade from damaging the horns 39, due to handling while the switch is being assembled or installed.

From the foregoing description, it will be seen that the improved switch permits a powerful and positive electrical connection between the blade tip and the jaws. The mechanism is extremely rugged and simple in its construction. Snow or ice cannot interfere with the opera-

tion of the switch because the jaws are covered and any ice forming around the jaw opening will be easily broken by the movement of the blade tip.

Obviously, the present invention is not restricted to the particular embodiment thereof herein shown and described. Moreover, it is not indispensable that all the features of the invention be used conjointly, since they may be employed advantageously in various combinations and sub-combinations.

What is claimed is:

An air-break switch comprising, in combination, a rocking insulator; a rigid switch blade pivoted for limited swinging movement on said rocking insulator; a stationary insulator; a jaw housing on said stationary insulator having a closed top; a stop member for the blade to arrest its swinging movement as the rocking insulator swings the blade toward closing position but permitting the tip to slide longitudinally thereon between the contacts and beneath the top of the housing during the final switch closing movement; a horn-shaped bracket carried by the rocking insulator having lateral flanges overlying the pivoted end of the switch blade to provide a sleet hood therefor; and arc-ing horns carried by said bracket.

TOMLINSON FORT JOHNSON.
